UNITED STATES PATENT OFFICE.

JOHN H. STUHR, OF MIDWAY, WISCONSIN.

FUR-STRETCHER.

1,367,522.

Specification of Letters Patent. Patented June 24, 1919.

Application filed February 7, 1919. Serial No. 275,662.

To all whom it may concern:

Be it known that I, JOHN H. STUHR, a citizen of the United States, residing at Midway, in the county of La Crosse and State of Wisconsin, have invented certain new and useful Improvements in Fur-Stretchers, of which the following is a specification.

The invention has for an object to provide an improvement in fur stretchers, and particularly aims to improve means for holding pelts upon a resilient wire frame having a proper form and expanding action to fit the fur and hold it properly distended. It is an important object also to make a device of this kind readily adjustable to furs of different sizes, so that its maximum efficiency may be attained. It is a further purpose to give a device of this kind in which the edge portions of the pelts of small furs will be satisfactorily held against shrinkage, at the same time that the fur is properly distended by the frame. It is also an aim to give a construction of a device of this kind in which there will be no parts liable to loss, and further to enable the construction of the parts with facility from stock material at a low cost.

Additional objects and advantages as well as features of invention may be apparent from the following description and drawings, in the latter of which,

Figure 1 is a top view of the device, with the gripping means in inoperative position, Fig. 2 is an edge view of the device, Fig. 3 is an end view,

Fig. 4 is a detail of one of the gripping devices in engaging position, the bight of the frame being supposed to be below,

Fig. 5 is a similar detail of the device in disengaged position.

There is illustrated a frame 10, substantially U-shaped in plan, the bight portion being suitably narrowed and shaped to fit the ordinary pelt, as at 11, one arm of the frame having an eye 12 formed therein at right angles to the mean plane of the frame, while the other arm has an extended end bar portion 13 bent at right angles to the arm, and extended slidably through the eye 12. The end portion of the arm 13 is formed with a series of apertures 14, through which a pin 15 may be engaged, to hold the sides of the frame compressed toward each other as adjusted. The pin 15 is formed of wire having a helix 16 at its base engaged around

the arm inwardly of the eye 12 loosely, to permit its longitudinal sliding movement upon the arm. The arm pieces have a series of apertures 17 therethrough extended at right angles to the mean plane of the frame, and in these there are pivoted pelt grips 18, now to be described.

Each grip is formed of a single piece of wire, having an intermediate pivot portion 19 engaged through the aperture of the frame, and having opposite end portions bent at right angles thereto on radii at an angle approximately 90 degrees, as at 20 and 21. The arm 20 at the extremity is bent inwardly to form a strike portion 22, adapted to rest against the side of the frame arm at opposite limits of the pivotal movement of the gripping device. The arm 21 is positioned so that when the stop 22 is engaged against the frame arm toward its outer end, the arm 21 will extend outwardly of the frame at an angle of about 45 degrees, as shown dotted in Fig. 1. The arm 21 may be slightly curved, and provided with a blunt point at its extremity, adapted to engage in the pelt without liability of puncturing it. At the opposite position of the gripping device, the stop 22 being engaged against the side of the frame arm in the direction of the bight of the frame, the pelt-engaging points of the arm 21 will be directed inwardly of the frame, as shown in Fig. 1. The stops 22 may be utilized as manipulating devices by which the gripping devices may be shifted from one position to the other. A rod 25 formed of heavy wire similar to that of which the frame itself is made, is formed with an eye 26 receiving the transverse bar 13, slidably therein, the outer part of the rod 25 being rectilinear in form and provided with a series of transverse apertures in which there are swiveled double hook devices 27, by which edge portions of pelts between the arms of the frame may be engaged and suitably supported. Or, the rod 25 may be swung outwardly to extend longitudinally in the opposite direction from the frame 10, and utilized to support a head portion or other part of a pelt which cannot be conveniently engaged over the arms of the frame 10. In the last mentioned position the position of the hook devices 27 may be reversed, so that their points will be directed outwardly from the frame so as to properly engage portions of a pelt, as necessary.

In use, in order to stretch a pelt, the operator simply inserts the end portion 11 of the frame within the pelt and forces it thereinto, until the pelt is properly drawn upon the frame, this operation causing all of the arms 21 to be directed outwardly toward the open end of the pelt. After the pelt is properly drawn upon the frame, the pivot devices will be in the position as shown in Fig. 5, and the operator then inserts a finger first at one side and then at the other, engaging the stops 22 and pulling them outwardly thereby forcing the arms 21 toward the outer side of the frame and into the position shown in Fig. 4 where it will so engage the pelt as to prevent it shrinking and drawing off of the frame. The hook devices 27 are then suitably engaged in the intermediate parts of the pelt or otherwise as required. After the pelt is dried in order to release the devices 27 from the edge portions the pelt is grasped and pulled toward the bar 13 slightly, while the finger is in-

serted within the pelt and the hooks 27 operated to release the pelt. The gripping devices 21 are released by pushing inwardly on the stops 22 until they have reached an inoperative position such as indicated in solid lines in Figs. 1 and 5. The pelt may then be drawn from the frame without any interference.

What is claimed:

In a stretcher of the character described, a frame adapted to be engaged in a pelt and pivoted grips thereon, each including an arm having a stop thereon to engage the inner side of the frame, and an arm fixed relatively to the first, movable inwardly and outwardly of the frame for the purposes described.

In testimony whereof I have affixed my signature in presence of two witnesses.

JOHN H. STUHR.
